UNITED STATES PATENT OFFICE.

GEORGE FRANCIS POND, OF EAST AURORA, NEW YORK, ASSIGNOR TO GUY J. EVANS, OF BUFFALO, NEW YORK.

PRINTING APPARATUS.

Application filed December 15, 1921. Serial No. 522,593.

To all whom it may concern:

Be it known that I, GEORGE FRANCIS POND, a citizen of the United States, residing at East Aurora, in the county of Erie and State of New York, have invented new and useful Improvements in Printing Apparatus, of which the following is a specification.

This invention relates to a printing apparatus which is more particularly designed for using a stencil through which an impression may be made by means of an inking device upon the surface which is to receive the printing, and more particularly to an apparatus of this character which will permit the stencil holder and the impression device to be manipulated by one hand while the other hand is engaged in manipulating the cards, sheets or other articles which are to be printed.

It is the object of this invention to produce an apparatus of this character which is very simple and compact in construction, easily operable, and permits of making printed impressions on successive sheets, cards or the like with ease and facility.

In the accompanying drawings:

Figure 1 is a side elevation, partly in section, of a printing apparatus embodying my improvements. Figure 2 is a bottom plan view of the same. Figures 3 and 4 are vertical transverse sections, taken on the correspondingly numbered lines in Fig. 1. Figure 5 is a fragmentary, longitudinal section, similar to Fig. 1, but showing the position of the stencil holder and the impression device which they assume when assembling or dismembering the same. Figure 6 is a horizontal section taken on the correspondingly numbered lines in Fig. 1. Figures 7, 8 and 9 are perspective views of the parts of the stencil holder and stencil dismembered. Figure 10 is a sectional perspective view showing a modified form of the means for attaching the stencil to the stencil holder.

Similiar characters of reference indicate corresponding parts throughout the several views.

In the construction shown in Figs. 1-6, the stencil consists of a rectangular rim, border or frame 20 of comparatively stiff material, such as card board, and a stencil

sheet or strip 21 secured to this border, so as to extend across the opening therein, this sheet being adapted to have perforations formed or cut therein for the purpose of converting the same into a stencil for producing impressions of the same on sheets, cards or other surfaces 11 to be printed by means of an inking device which is pressed against the upper side of the stencil sheet and leaves an impression on the surface which is engaged by the underside of the stencil.

The holder shown in Figs. 1-9 for supporting this stencil is constructed as follows:

22 represents a rectangular holding frame which is normally arranged horizontally and against the underside of which the rim or border of the stencil is held, so that the stencilized surface of the stencil extends across the opening of the holder frame.

Although various means may be employed for securing the stencil against the underside of the holder frame, those shown in the drawings are preferred inasmuch as they have been found satisfactory in practice, the same consisting of a rectangular retaining rim 23 engaging with the underside of the margin or border of the stencil, so as to expose the underside of the stencil sheet. This rim may be detachably connected with the holder frame by various means, for instance, by providing the opposite longitudinal edges of the holder frame with two inwardly-projecting longitudinal flanges 24 and the corresponding longitudinal edges of the retaining rim with two upwardly-projecting catches 25 which engage with the outer sides of the flanges 24 and terminate at their upper ends with hooks 26 which project inwardly and engage with the upper edges of the flanges 24, as best shown in Figs. 2 and 4. For the purpose of attaching the stencil to the underside of the holder frame, it is only necessary to press the same against the underside of this frame by means of the retaining rim, which latter upon reaching the upper end of this movement will be held in place by engagement of the hooks 26 of the catches with the upper edges of the flanges 24. Disengagement of the retaining rim

for the purpose of releasing the stencil is

effected by simply pressing the two catches 25—26 apart, which permits the retaining rim to be disengaged from the stencil in order to release the latter and permit the 5 same to be replaced by another stencil.

The impression device may be of any approved form, that shown in the drawings being suitable and consisting of an ink delivery roller or member 27, a carrier 28 on 10 which said inking roller is mounted, and a handle 29 arranged at one end of this frame and whereby the carrier is moved lengthwise of the stencil holder for the purpose of running the ink roller 27 over the top 15 of the perforated sheet of the stencil and producing an impression of the same on the surface below the same. Any suitable means may be provided for replenishing the ink on the inking roller 27 from time to 20 time.

In order to permit the operator to lift the stencil holder from the surface which is being printed by the same hand which operates the impression device, each of the 25 flanges 24 is provided at its opposite ends with a coupling flange which projects laterally inwardly therefrom and comprises a horizontal upper portion 30 arranged at the upper edge of the flange 24 adjacent to one 30 end thereof, and an upright end portion 31 which extends downwardly from the outer end of the respective horizontal portion 30 and forms with the latter an angular retaining flange or stop. The inner ends of the 35 horizontal portions 30 of the flanges at opposite ends of each upright flange or side wall 24 are separated from each other, so as to form a vertical passage or throat 32 between the inner ends of these flange portions. 40

On opposite sides of the lower part of the carrier 28 of the impression device are arranged a pair of rollers 33, the rollers on the same side of the carrier being arranged 45 horizontally and lengthwise side by side and projecting laterally therefrom close to the inner sides of the upright walls or flanges 24. Upon moving the carrier lengthwise of the stencil holder into one extreme position 50 or the other relatively thereto, the rollers or projections 33 at one end or the other of the carrier will engage one or the other of the vertical walls 31 of the angular coupling flanges, and thereby arrest the movement of 55 the carrier in either direction lengthwise of the stencil holder. While the carrier of the impression device is arranged at one end or the other of its stroke, a lifting movement of this carrier will also cause the stencil 60 holder to rise therewith and be elevated from the surface which is being printed, this being due to the fact that the pair of rollers 33 at one end of the carrier will engage the upper side of the holder frame while the 65 coupling rollers 33 at the other end of this

carrier will engage the underside of the horizontal portions 30 of the coupling flanges at the respective end of the stencil holder. The position of the carrier just described with reference to the stencil holder 70 is indicated by dotted lines at the left hand end of Fig. 1. By this means it is possible to couple the stencil holder with the impression device in such manner that the stencil can be deposited upon the surface to be 75 printed, then the impression device may be moved either forwardly or backwardly relatively to the stencil holder for causing the ink roller to produce an impression of the stencil on the surface, and then the stencil 80 holder may be lifted bodily together with the impression device while the latter is at either end of its stroke by the use of one hand, while the other hand is left free to manipulate the cards, sheets or other articles which are to be successively printed. 85

When it is desired to detach the impression device from the stencil holder for the purpose of cleaning the apparatus or when it becomes necessary to change the stencil, 90 this can be readily done by first moving the carrier of the impression device into its central position when the laterally-projecting rollers or projections 33 will be vertically in line with the passages 32 between 95 the inner ends of the horizontal portions 30 of the coupling flanges, at which time the projections 33 can be readily moved upwardly through the passage 32 and thus enable the impression device to be detached 100 from the stencil holder. By reversing this movement, the impression device and stencil holder can be again coupled or assembled for continuing the printing operations. 105

In order to hold the stencil in a definite position upon the upper surface of the retaining rim, preparatory to clamping the stencil between this rim and the underside of the holder frame, the retaining rim is provided adjacent to its opposite ends with gage pins 34 with which the opposite ends of the stencil are adapted to engage, as shown in Fig. 6, and thus be held against longitudinal displacement while the longitudinal edges of this stencil engage with 110 the spring catches 25 on the corresponding edges of the retaining rim and are thereby held against transverse displacement. In order to permit of making these gage pins of a reasonable length and insure holding 115 the stencil in place and still permit the stencil to be securely clamped against the underside of the holder frame, the latter is provided in line with the gage pins with 120 openings 35 which receive the upper ends of these gage pins, as shown in Fig. 3, and thus not only serve as means for gaging and retaining the stencil in its proper position between the retaining rim and holder frame, 125 but also securely interlocking this rim and 130

holder frame against horizontal displacement both lengthwise and transversely relatively to each other.

Instead of constructing the stencil in the form of a comparatively stiff border across the opening of which the stencil sheet is secured, as shown in Figs. 1-6, the stencil may be made of a sheet 36 of stencilizable material which is stretched across the underside of the holder frame and turned with its opposite ends 37 upwardly and inwardly over the top of the transverse end portions of the holder frame, as shown in Fig. 10, and securing these end portions of the stencil sheet on the respective end portions of the stencil holder by means of channel-shaped clips 38, each of which engages its lower jaw with the underside of the stencil sheet and its upper jaw with the reversely-turned upper part of the stencil sheet, so that the latter is firmly clamped to the stencil holder. For convenience, each of these clips is provided on its upper jaw with a fingerpiece 39 whereby the same may be manipulated when applying the clip to the turned portion of the stencil on the holder frame or removing the same therefrom. Each of these clips is constructed of spring metal, so that it will be retained frictionally in place on the stencil sheet and holder frame when the parts are assembled.

This printing apparatus is not only exceedingly simple and inexpensive in construction, but the same is also very compact and easily operable and the same permits of expeditiously accomplishing printing of this character, inasmuch as both hands may be occupied to the fullest extent for this purpose.

I claim as my invention:

1. A printing apparatus comprising a stencil holder having a frame, means for attaching a stencil to said frame, and means for engaging the top of the stencil and producing an impression of said stencil from the underside thereof on a surface comprising an inking member adapted to engage the stencil and a carrier upon which said inking member is mounted and which is coupled with said frame so as to permit said carrier to move lengthwise of said frame but compel the same to move vertically with said carrier.

2. A printing apparatus comprising a stencil holder having a frame provided at opposite edges of its upper side with upwardly projecting walls, and lateral coupling flanges on said walls, and an impression device having an inking member adapted to engage with the top of said stencil for obtaining an impression from the underside of the latter, and a carrier supporting said inking member and having lateral coupling

projections adapted to engage said flanges.

3. A printing apparatus comprising a stencil holder having a frame provided at opposite edges of its upper side with upwardly projecting walls and lateral coupling flanges at opposite ends of said walls, the flanges of each wall having their opposing inner ends separated by an intervening passage, and a longitudinally-movable impression device having an inking member adapted to engage the stencil and a carrier supporting said inking member and having lateral projections adapted to engage with the flanges of said walls at either end of the longitudinal movement of the impression device and capable of moving vertically through said passages while in a position intermediate of the flanges at opposite ends of said walls.

4. A printing apparatus comprising a stencil holder having a frame provided at opposite edges of its upper side with upwardly projecting walls, and lateral angular coupling flanges arranged on said walls at opposite ends thereof, each flange having a horizontal upper part and a vertical part extending downwardly from the outer end of the upper part, and an impression device comprising an inking member adapted to engage said stencil, and a carrier supporting said inking member and having lateral projections which are adapted to engage the angular flanges at opposite ends of said walls and also capable of passing vertically between the opposing inner ends of said flanges.

5. A printing device comprising a stencil holder having a frame and walls arranged at opposite edges of the upper side of said frame, a stencil extending across the underside of said frame, a rim engaging the underside of said stencil, and catches arranged at opposite edges of said rim and engaging detachably with said walls.

6. A printing device comprising a stencil holder having a frame, a stencil adapted to extend across the underside of said frame, and means for clamping said stencil against the underside of said frame comprising a rim engaging with the stencil and being provided at opposite ends with pins engaging with opposite ends of said stencil.

7. A printing device comprising a stencil holder having a frame, a stencil adapted to extend across the underside of said frame, and means for clamping said stencil against the underside of said frame comprising a rim engaging with the stencil and being provided at opposite ends with pins engaging with opposite ends of said stencil and said frame being provided with openings which receive said pins.

GEORGE FRANCIS POND.
